(57) **CLAIM**

The ornamental design for a carbon fiber panel with integral illumination unit, as shown and described.

DESCRIPTION

FIG. 1 is a front view of a carbon fiber panel with integral illumination unit of the present invention, in an un-illuminated condition;

FIG. 2 is a front view of the invention illustrated in FIG. 1, in an illuminated condition;

FIG. 3 is a cross-sectional view of the invention illustrated in FIG. 1, taken along lines 3-3 of FIG. 2;

FIG. 4 is a front view of a second embodiment of a carbon fiber panel with integral illumination unit of the present invention, in an un-illuminated condition;

FIG. 5 is a front view of the invention illustrated in FIG. 4, in an illuminated condition;

FIG. 6 is a cross-sectional view of the invention illustrated in FIG. 4, taken along lines 6-6 of FIG. 5;

FIG. 7 is a front view of a third embodiment of a carbon fiber panel with integral illumination unit of the present invention, in an un-illuminated condition;

FIG. 8 is a front view of the invention illustrated in FIG. 7, in an illuminated condition; and,

FIG. 9 is a cross-sectional view of the invention illustrated in FIG. 7, taken along lines 9-9 of FIG. 8.

The broken lines surrounding each of the figures depict the boundaries of the claim and form no part thereof. The other broken lines in the drawings illustrate portions of the carbon fiber panel with integral illumination unit and form no part of the claimed design. The parallel diagonal shading lines in the drawings indicate transparency.
